WAIST BEARER AND CROSS TIE

Lawrence L. Neebe, Woodbury, N. J.

Application August 3, 1935, Serial No. 34,586

10 Claims. (Cl. 105—44)

This invention relates generally to an improved waist bearer for locomotives of the "Mallet" articulated type, and it is one object of my present invention to provide a compact, simple, safe and sturdy waist bearer cross tie which will function without the necessary complications involved in various prior art arrangements.

A further object is to provide improved wearing strips, and means whereby they may be effectively and easily lubricated together with ease of renewal.

Other objects and advantages will be more apparent to those skilled in the art from the following description of the accompanying drawings in which:

Fig. 1 is a diagrammatic outline of a "Mallet" articulated type of locomotive with my improvements embodied therein;

Fig. 2 is an enlarged side elevational view of the assembled waist bearer and cross tie looked at from the side of the locomotive and in the same direction as Fig. 1;

Fig. 3 is a view of the bearer and cross tie looking forward in the direction of the arrow *a*, Fig. 2;

Fig. 4 is a plan view of approximately one-half of the cross tie;

Fig. 5 is an end view of one-half of the cross tie looking in the direction of the arrow *b* of Fig. 2;

Fig. 6 is a longitudinal vertical section taken substantially on the line 6—6 of Fig. 3;

Fig. 7 is a perspective view of several of the bearing elements shown in spaced relation for purposes of clarity.

In the particular embodiment of the invention which is shown herein merely for the purpose of illustrating one specific form among possible others that the invention might take in practice, I have shown in Fig. 1 a "Mallet" articulated type of locomotive having a boiler 1 attached rigidly to the rear frame 2 at points adjacent the rear cylinders 3 and firebox 4. A forward frame 5 is pivotally connected as at 6 to the rear frame 2. A forward portion of the boiler 1 is supported upon frame 5 through a waist bearer and cross tie generally indicated at 7. It will of course be understood that each of the frames 2 and 5 is provided with usual running gear actuated respectively from the rear cylinders 3 and front cylinders 8. Inasmuch as the structure of such devices is well-known, it is not necessary to describe the same here.

The waist bearer proper is indicated at 9 and is rigidly secured to the boiler or smokebox by

studs, rivets, bolts or welding. The waist bearer is supported upon the cross tie structure generally indicated at 10. The cross tie has, as shown in Fig. 3, a horizontal web 12 whose longitudinal edges are provided with angled flanges 13 which as shown in Fig. 2 terminate longitudinally at a recess 14. The horizontal portion of flanges 13 rests upon the locomotive frame 5 which as shown in Fig. 3 is specifically of the bar type. A usual depending lug 15 projects downwardly between the two sides of the bar frame and is secured thereto in any usual manner. It will be noted from Fig. 2 that there are two such lugs 15 joined by an arch web or flanges 16 to provide an extremely strong and yet compact cross tie, 15 and I have provided a steam pipe conduit 17 so arranged that the horizontal web 12 intersects the wall of conduit 17, thereby obtaining a high degree of structural cooperation between these two elements so that they mutually directly reinforce each other. The steam pipe 17 as shown in Fig. 2 is of such shape as to permit various connecting pipes to be properly secured thereto.

Formed integrally with the horizontal web 12 and conduit 17 is a supporting box generally indicated at 19. This box has side walls 20 and 21, Fig. 2, and front and back walls 22 and 23, Figs. 2 and 6. The side walls 20 and 21 are located very close to the bar frame 5, thereby insuring maximum support for the waist bearer which will be shortly described. Also the front and rear walls 22 and 23 function as transverse reinforcements for the horizontal web 12. Formed integrally with the box 19 at the top thereof is a transversely elongated supporting member 25 having, as shown in Figs. 4 and 7, edge flanges 26 terminating short of the ends of element 25 as generally indicated at 27, Figs. 4 and 7. Snugly disposed within the elongated recess formed between flanges 26 and 27 is a wearing plate 28 having a concave bearing surface 29. A relatively large flat wearing plate 30 is provided on its under side with a convex bearing surface 31 adapted to be seated within and complementary to the concave seat 29. The bearing strip 28 is of greater length than the flanges 26, thereby extending to the opposite ends of member 25. The bearing plate 30, however, is only of the same length as flanges 26. Projections 32 are formed integrally with the opposite ends of plate 30 so as to form continuations of the convex surface 31, the total length of such surface 31 being the same as that of plate 28. Hence the ends of members 25, 28 and 32 will be substantially flush with each other in a vertical plane. Nor-

mally these plates are nested together as shown in Fig. 2 and are held in such relation by locking yokes at each end thereof. One such locking yoke is shown at 33 and has an opening 34 of 5 such configuration as to permit the yoke to be slipped over the end 27, plate 28 and projection 32 as shown in Fig. 2. This yoke is then welded to member 25 at any suitable points. It will be understood, however, that the opening 34 is of 10 such size that plate 30 is permitted to rock on the convex-concave surfaces 29 and 31.

Interposed between plate 30 and the flat surface 36 of waist bearer 9 is a pair of wearing plates 37 and 38. One or both of these plates 15 are provided with a suitable oil recess 39 which may be supplied from oil reservoirs 40. These reservoirs are formed in a laterally recessed portion of the waist bearer and may be provided with upstanding flanges 41 to form a reservoir of 20 ample capacity from which the oil is fed to recess 39 through openings 42, Fig. 3. To insure that the bearing strips and boiler are maintained together at all times, the waist bearer as shown in Figs. 2 and 3 has centrally located depending hooks 43 extending downwardly and under plate 30. Thus it is seen that the boiler and cross tie 10 can have relative rocking movement between the surfaces 29 and 31 as well as lateral sliding movement between the bearing 25 plates 37 and 38 thus accommodating all movements of the boiler and cross tie.

To insure maximum stability of the supporting box 19 and rigidity of the cross tie as a whole, I employ a longitudinally extending vertical web 44, 35 Figs. 2 and 3, one adjacent each side of the locomotive bar frame, while substantial longitudinal continuations of these webs are indicated at 45 in Fig. 2. It will be noted that the combined webs 44 and 45 are of substantially arch formation 40 and terminate at their forward ends in a main vertical transversely extending web 47. This transverse web is in turn reinforced on its front side by horizontal ribs 48 and 49. The web 47 is thus adapted to effectively function to provide as 45 shown in Fig. 4 vertical pads 50 for suitable valve gear link bearings while brake cylinder pads 51 may be formed in effective supporting relation to the upper rib 48. The front web 47 also permits an effective support 53, Fig. 2, for a counter- 50 balance spring of a reverse shaft while horizontally extending guide lugs 54 are formed in reinforcing relation to vertical web 47 and lower ribs 49. A similar mutual reinforcing relation is obtained as shown in Figs. 2 and 4 between 55 brake hanger brackets 56 and the upper one of flanges 16 and the longitudinal arched web 44.

It will of course be understood that all of the foregoing elements of the cross tie are preferably cast as an integral unit whereby the foregoing 60 mutual supporting relation between the elements is obtained in a very effective manner. This construction is of course highly beneficial in insuring a very stable support for the improved bearing plates 28 and 30 whereby the same may efficiently maintain complete operative relation between the boiler and the cross tie.

It will of course be understood that various changes in details of construction and arrangement of parts may be made by those skilled in the 65 art without departing from the spirit of the invention as set forth in the appended claims.

I claim:

1. The combination in a "Mallet" articulated type locomotive comprising a cross tie having a 70 transversely extending supporting surface, a

boiler waist bearer, means interposed between said bearer and supporting surface to permit rocking and lateral movements between the same, and means for maintaining said rocking means in operative relation to said supporting surface 5 independently of said waist bearer.

2. The combination in a "Mallet" articulated type locomotive having a cross tie provided with a transversely extending supporting surface, a boiler waist bearer, a bearing plate interposed 10 between said bearer and supporting surface, seating means for rockably supporting said plate on said surface, and a locking yoke at each end of said cross tie and plate for maintaining the same 15 in operative relation.

3. The combination in a "Mallet" articulated type locomotive having a cross tie provided with a transversely extending supporting surface, a boiler waist bearer, a bearing plate interposed 20 between said bearer and supporting surface, seating means for rockably supporting said plate on said surface including a member supported upon said surface and having a curved seating surface, and means forming a complementary curved mating surface on said plate. 25

4. The combination in a "Mallet" articulated type locomotive having a cross tie provided with a transversely extending supporting surface, a boiler waist bearer, a bearing plate interposed 30 between said bearer and supporting surface, seating means for rockably supporting said plate on said surface, and means completely encircling only a portion of said plate and said cross tie and engageable with said plate and cross tie to maintain the same in their operative relation. 35

5. The combination in a "Mallet" articulated type locomotive having a cross tie provided with a transversely extending supporting surface, a boiler waist bearer, a bearing plate interposed 40 between said bearer and supporting surface, seating means for rockably supporting said plate on said surface, said bearing plate having a lateral end projection, and a holding yoke encircling only said projection and cross tie.

6. The combination in a "Mallet" articulated type locomotive having a cross tie provided with a transversely extending supporting surface, a boiler waist bearer, a bearing plate interposed 50 between said bearer and supporting surface, seating means for rockably supporting said plate on said surface, said bearing plate having a lateral projection, and a holding yoke encircling said projection and cross tie and welded thereto.

7. The combination in a "Mallet" articulated type locomotive having a cross tie provided with a transversely extending supporting surface, a boiler waist bearer, a bearing plate interposed 60 between said bearer and supporting surface, seating means for rockably supporting said plate on said surface, said cross tie having a transversely disposed elongated recess in which said seating means is disposed; lateral projections on each end of the plate; and means for holding said seating means, projections and cross tie in operative relation. 65

8. The combination in a "Mallet" articulated type locomotive having a frame and cross tie for supporting a waist bearer, said cross tie having a longitudinally extending steam conduit, a horizontal web intersecting said conduit at a point 70 below its upper surface, and longitudinal edge flanges formed on said horizontal web for supporting said cross tie on said frame.

9. The combination set forth in claim 8 further characterized by the provision of lugs depend- 75

ing from said edge flanges and extending transversely between said edge flanges and beneath said steam conduit.

10. The combination in a "Mallet" articulated type locomotive comprising a cross tie for supporting a waist bearer, said cross tie having a longitudinally flanged base structure adapted to rest upon a locomotive frame, an elevated supporting structure projecting upwardly from said

base, longitudinal ribs extending upwardly from said base to said supporting structure, a transverse vertical web at the forward end of said said base and said longitudinal ribs, all integrally cast as a single unit, transversely extending horizontal flanges formed on the front side of said web, and auxiliary supporting pads formed integrally with said web and flanges. ⁵
